[57] CLAIM

The ornamental design for golf putter head, as shown and described.

DESCRIPTION

FIG. 1 is a front perspective view of a golf putter head showing our new design;

FIG. 2 is a top plan view thereof;

FIG. 3 is a side elevational view of the elongated side of the putter head of FIG. 1, showing the planar striking surface;

FIG. 4 is a side elevational view of the opposite side of the putter head of FIG. 1;

FIG. 5 is a rear elevational view of the putter head of FIG. 1;

FIG. 6 is a bottom view of the golf putter head of FIG. 1; and

FIG. 7 is a front view of the golf putter head of FIG. 1.
